UNITED STATES PATENT OFFICE.

JOHN ALEXANDER WHYTE, OF TORONTO, CANADA.

ELECTRIC SIGNALING AND ELECTROPNEUMATIC TRAIN-CONTROL SYSTEM.

SPECIFICATION forming part of Letters Patent No. 794,266, dated July 11, 1905.

Application filed March 5, 1904. Serial No. 196,776.

To all whom it may concern:

Be it known that I, JOHN ALEXANDER WHYTE, electrician, a subject of the King of Great Britain, residing in the city of Toronto, 5 in the county of York, in the Province of Ontario, Canada, have invented new and useful Improvements in Electric Signaling and Electropneumatic Train-Control Systems, of which the following is a specification.

10 My invention relates to improvements in electric signaling and electropneumatic train-control systems of the normal-clear class; and one object of my invention is to notify the engineer by electrically-operated means within 15 in his cab when a rail or the wiring in his block has been broken, when a switch is open therein, when a current-conducting obstruction or train is within his block, and when the electrically-operated means within his cab is 20 itself out of order.

Another object is to enable the station agent to signal the engineer of an inbound and outbound train.

A still further object is to provide electro-pneumatic means within the cab for automatically applying the air-brake when the engineer neglects to obey signals.

The invention consists, essentially, in dividing the track into a series of blocks, each block 30 comprising a third rail or trolley-wire divided into insulated sections, in dividing the first track-rail into insulated sections, (preferably of same length as third-rail or trolley-wire sections,) in utilizing the second track-rail as 35 a common conductor for all the blocks, in suitably wiring the proper insulated sections of the third rail or trolley-wire and said first track-rail to each other and to said second track-rail, in completing the circuit by means 40 of the train, and in providing electrically-operated means within the engineer's cab whereby he will be notified of the condition of the block he is in or of the said electrically-operated means itself.

45 My invention further consists in combining with the above-enumerated elements electro-pneumatic means situated in the engineer's cab for automatically applying the air-brake when the engineer neglects to obey signals.

50 My invention further consists in providing

a suitable circuit-controlling means and an annunciator in the station and wiring same to the inbound station-block and outbound station-block and to said second track-rail, whereby the presence of a train in the block station 55 may be indicated or by means of which the station agent may signal the engineer of said train.

The drawings illustrate one track of a double track, and the trains are all supposed to be 60 traveling eastward. The track for trains traveling westward will of course be a duplicate of the track shown. The current is always flowing through part of the apparatus in the engineer's cab and the block in circuit with 65 said part of the apparatus when the said part of the apparatus and the blocks are in working order. The blocks are preferably a mile in length, made up of sections of half a mile, the current always flowing through the block 70 in advance of the train. The cab is the source of electrical energy.

Figure 1 is a diagrammatic view of my track divided into blocks, showing a train thereon. Fig. 2 is a similar view showing the station 75 wired to the inbound station-block and to the outbound station-block and to second track-rail, the same being in circuit with a through train. Fig. 3 is a similar view showing the station in circuit with a through train and 80 also showing suitable wiring and switches for controlling the circuit at switch centers. Fig. 4 is a similar view showing the station in circuit with a train, the station agent having signaled the engineer to stop in the inbound 85 station-block. Fig. 5 is a similar view showing the station in circuit with a train, the station agent having signaled the engineer to pass through. Fig. 6 is a similar view showing the station in circuit with a train, the station agent having signaled the engineer to stop in the first block west of the inbound 90 station-block. Fig. 7 is a similar view showing the station in circuit with an outbound train, the station agent having signaled the engineer to stop in the outbound station-block. Fig. 8 is a front elevation of the electrically-operated signaling means used in the engineer's cab and electropneumatic means 95 for applying the air-brake. Fig. 9 is in part 100

a side elevation of the parts shown in Fig. 8, parts being removed and a vertical section being taken on the line *a b*. Fig. 10 is an enlarged front elevation of the casing containing the station mechanism. Fig. 11 is an enlarged detail of parts shown in Fig. 9. Fig. 12 is a view similar to Fig. 7, showing an alternative controlling means whereby the station agent signals an outbound train to stop in the outbound station-block. Fig. 13 is an enlarged detail view in perspective of parts shown in Fig. 9; and Fig. 14 is a diagrammatic view of an electric trolley-road divided into my blocks, showing a trolley-car thereon.

In the drawings like characters of reference indicate corresponding parts in each figure.

When the train or electric car is to pass through, its approach to the station will operate the distant semaphore in the station first when it enters the home portion of its (the train's) block (see Figs. 2 and 5) and then operate the home semaphore of the station when it (the train) enters the inbound station-block (See Fig. 3.)

Electropneumatic means for operating the air-brake mechanism is not shown in the diagrammatic views, as the electrically-operated means for signaling the condition of the block to the engineer or motorman will operate independent thereof.

The track is divided into a series of blocks of any desired length. The first track-rail A is divided into a series of insulated sections, while the second track-rail D is not divided into sections and is used as a common path for the return-current of the several blocks. Preferably (though not essentially) situated between the rails A and D is the third rail E, which is divided into insulated sections, preferably of the same length as the insulated sections of the first track-rail A. A single block consists of one of the sections E' of the third rail; section A² of the first track-rail; the wiring B, connecting the section E' to the section A²; the wiring C, connecting the section A² with the second track-rail D, and the portion of the second track-rail D from point C', where the wiring C connects therewith, back to the train. A train is shown to be in circuit with the block just described, and the path of the current will be shown by arrows in full.

A³ represents insulating-points for the sections of the first track-rail A, and E² represents insulating-points for the sections of the third rail E.

I preferably use a resistance-coil J in the wiring of each block, but may dispense with same.

K represents the train or engineer's cab, which is suitably provided with any suitable conducting-shoes L and M, which operate on the third rail E. (Shown in contact with one of the sections E' thereof.) The cab K is provided with a source of electrical energy O',

an ordinary signal-magnet O, an electrical apparatus P, and an electromagnet Q, both operated by an excessive current flowing through the circuit, the feed-wire R, and return-wire R', putting in circuit said source of electrical energy and devices in the cab with the block before described through the conducting-shoes L and M, the current returning from second track-rail D through the axle of the cab back to source of electrical energy O', as shown by full arrows in Fig. 1. From the description and illustrations it will be clearly understood that the live block overlaps part (preferably one-half) of the preceding block. By following out the live block (shown by arrows in full in Fig. 1) and the preceding dead block (shown by dotted arrows) the way the live block overlaps part of the preceding dead block will be clearly understood. The insulated sections E' of the third rail, together with their corresponding length of second track-rail D adjacent thereto, constitute the home portion of the block for the train, whereas the insulated sections A² of the first track-rail A, together with their corresponding length of second track-rail D wired thereto, constitute the distant portion of the block for train. In all cases the shoe M enters the block first, and, as shown, the shoe L must enter therein simultaneously with the locomotive or train K. If desired, the said second shoe L may enter the block before the train or locomotive. The train is moved in the direction indicated by arrow, and current is always flowing through the apparatus O, P, and Q in the cab and the block said apparatus is in circuit with. From Figs. 8 and 9 it will be seen that the electromagnet Q and electrical apparatus P (both operated by an excessive current flowing through the circuit) and signal-magnet O are all in circuit with the block before described, through the source of electrical energy O', by means of the feed-wire R and return-wire R', the direction of the current being shown by arrows. By reason of the constant flow of current therethrough the armature 4 of the signal-magnet O keeps the home semaphore 5 in the position shown of normal "clear" counterbalancing the weight 6. Should the circuit be broken, either by reason of a defect in the signal-magnet O itself or by reason of the device P or electromagnet Q being electrically out of operation or by reason of a broken rail, an open switch, or from any other reason, the cessation of current through said signal-magnet O will cause the weight 6 to move the home semaphore 5, secured to the spindle 5' of said signal-magnet, into the position shown in dotted lines in Fig. 8, thus warning the engineer that there is danger in his block. Should a current-conducting obstruction, such as another train, be within the distant part of his block, as shown by dotted lines at R², Fig. 1, the circuit will be shorted.

circuited, taking the path through said obstruction, as shown by dotted arrows, back into the cab, as shown by arrows in full, thus causing an excess of current to flow through the apparatus P, which will cause the apparatus P to operate so as to move its distant semaphore 7, secured to its spindle 8, up into the position shown by dotted lines, Fig. 8, thus signaling the engineer.

Although I have shown the electromagnet Q as being in the same circuit with the signal-magnet O and the apparatus P, it must be understood that for the performance of the operation before described said electromagnet Q is not necessary. I preferably use the electromagnet Q with the apparatus P, so that in case either one should be out of order the working one will operate the apparatus hereinafter described for the purpose of applying the air-brake. The apparatus before described for communicating to the engineer the condition of his block will enable the engineer to take the necessary precautions; but in case he should be asleep the said apparatus alone will not apply the air-brake.

In order to automatically apply the air-brakes after the above-described operation of either of the apparatus O and P, I provide the following means: 9 is any suitable clock mechanism suitably supported within the casing A². The minute-hand shaft 10 of said clock mechanism is extended out through suitable supports and is provided at its outer end with the minute-hand 11. In Figs. 8 and 9 I have shown three electromagnets 12, 13, and 14, which are operated consecutively in order to permit air to escape from their respective air-pipes 15, 16, and 17, which are connected to the train-pipe 18 by any suitable coupling 19, and thus gradually apply the air-brakes. I of course may use only one of these electromagnets, and the description of the operation of one will do for all. In order to enable the said electromagnets 12, 13, and 14 to operate the air-brakes at different times, suitable mechanism is provided, and as the mechanism for each magnet is the same in construction and operation the description of that for one magnet will do for all. Surrounding the minute-hand shaft 10 is a sleeve 20, which is prevented from rotating by any suitable attachment 21, secured to the casing A², which houses the said signaling apparatus and air-brake-applying mechanism. Keyed to the sleeve 25, which has free movement round the sleeve 20, is an insulated disk 26. The distance of the circuit-conducting portion of the disk 26 from the brush 34 for same, Fig. 11, represents the time elapsing between the operation of either of the apparatus O and P and the application of the air-brake by the magnet 12. The overseeing engineer will time the application of the air-brakes for said electromagnets to operate at any desired time after the operation of either

of the signaling apparatus before described or the electromagnet Q by mechanism hereinafter described. If there is an open circuit, the movement of the home semaphore 5 into the dotted position shown in Fig. 8 will, by means of the crank-arm 27, secured to or forming part of its spindle 5', resting in the bottom of the slot 28, formed in the rod 29, (which rod is held so as to have the necessary vertical movement,) move the said rod 29 down in the direction indicated by arrow, thus moving the contact-piece 30 (secured to the spindle 55' of the electromagnet Q) out of contact with the escapement-wheel 31 of the clock mechanism, permitting the clock to operate.

33 is a pinion having movement on the minute-hand shaft 10 by means of the usual ratchet 33', keyed to said minute-hand shaft 10, and the pawl 33", secured to said pinion 85 and engaging said ratchet. By the operation of the minute-hand shaft and by means of the said pawl and ratchet the pinion 33 is moved round, thus moving the brush-holder 32, secured thereto, round in the direction indicated 90 by arrow in Fig. 11, so as to bring the brush 34 in contact with the metal strip 35, secured to the insulated disk 26, thus closing the circuit from the battery 36, through the feed-wire 37, to the brush 39, held in any suitable brush-holder 40, through the commutator-disk 42, keyed to the minute-hand shaft 10, thence by the wire 43 to the metal strip 35 of the insulated disk 26, thence through the brush 34, wire 44, to the commutator-disk 46, keyed to 100 the minute-hand shaft, then to the brush 47, wire 48, to the electromagnet 12, returning back through the wire 38 to the battery 36, the described circuit being shown by arrows. The current passing through the electromagnet 12 attracts its armature 49, thus by means of its valve 50, secured to the spindle 51, secured to the armature 49, opening passage-way 52, thus permitting air to escape from the air-pipe 15 through the coupling 53 and 110 out of same by means of the port 54, this operation reducing the air-pressure a certain amount and allowing the air-brake to be applied.

During the operation of the signal-magnet O in depressing the rod 29 it will be seen upon reference to Fig. 13 that the spindle 8 of the apparatus P is not operated upon, because its crank-arm 8' rests in the bottom of a slot 8", formed in said rod 29. The clock mechanism 9 of course will continue to operate until stopped by the mechanism now to be described.

When the brush 34 is being moved in the direction indicated by arrow in Fig. 11, the operation of the pinion 33 will depress the toothed rack 55 in mesh therewith (which toothed rack is held in suitable brackets 56) down in the direction indicated by arrow. Should the engineer not return the brush 34 to normal, the operation of the clock mech- 130

anism will depress the toothed rack 55 down to the limit of its movement and same will then stop the clock mechanism. 58 is any suitable valve which controls the supply of air from the train-pipe 18 into the pipes 15, 16, and 17. The stem 57 of this valve extends out and is provided with a handle 59, by means of which the engineer may operate same. In order to cut off the supply of air through the pipes 15, 16, and 17, to stop the clock mechanism, to return the brush-holder 32 back to normal, to return the rod 29 to normal, and to temporarily open the circuit for the apparatus O, P, and Q, the engineer moves the valve-stem 57 in the direction indicated by arrow, thus closing the valve 58 and bringing the arm 60, secured to said valve-stem, in contact with the contact-piece 30, secured to the spindle 55', moving same back to normal and holding it in contact with the escapement-wheel 31, thus stopping the clock mechanism 9. After said clock mechanism has been stopped the cam 61, secured to the valve-stem 57, abuts the toothed rack 55, moving same upward into the position shown in full lines in Figs. 8 and 9, thus returning the brush-holder 32 and brush 34 into the position shown in Fig. 11, thus opening the circuit for the magnets 12, 13, and 14. This opening of the circuit enables the spring 6 to move the valve 50 back to normal, preventing escape of air from pipe 15. The armature 49 is also returned to normal by said spring. As the rod 29 normally rests upon the contact-piece 30, same is returned to normal when said contact-piece is returned to normal. As the home semaphore 5 was moved into the dotted position shown in Fig. 8 by reason of the open circuit the movement of the rod 29 back to normal by means of the crank-arm 27, resting in its slot 28, returns the home semaphore 5 back to normal. Just after the arm 60 has returned the contact-piece 30 back to normal, so as to stop the escapement-wheel 31, any suitable switch mechanism 62, secured in part to valve-stem 57, is operated, so as to open the circuit for the apparatus O, P, and Q. Having returned the parts to normal the engineer returns the valve-stem 57 to normal, thus opening the valve 58 and returning the arm 60 and cam 61 back to normal and closing the circuit controlled by this switch 62, thus putting the apparatus in condition for signaling. If the circuit has been short-circuited and the apparatus P be in working order, the distant semaphore 7 will be moved up into the dotted position shown in Fig. 8, and its crank-arm 8', operating in the slot 8², will depress the rod 29, overcoming the resistance of the spring 54' of the electromagnet Q, thus moving the contact-piece 30 out of contact with the escapement-wheel 31 and permitting the clock mechanism 9 to operate, and thus apply the air-brake by means of the electromagnet 12, as

before described. When the rod 29 is being moved back to normal after the operation of the mechanism P, the crank-arm 8' of same operating in the slot 8² will be operated, so as to return the distant semaphore 7 back to normal. As the mechanisms for timing the operation of the air-brake by the magnets are the same for all, the description of one will be sufficient.

22 is any suitable spindle, to the inner end of which is keyed a gear-wheel 23, which meshes with the gear-wheel 24, secured to or forming part of the sleeve 25.

From the drawings and description it will be understood that the insulated disk 26 is controlled in its movement by the gear-wheels 23 and 24 and is of course held normally stationary. The overseeing engineer has set the insulated disk 26 (see Fig. 11) so that the electromagnet 12 will apply the air-brake within eight seconds after the operation of the apparatus O and P and Q—that is, the brush 34 will make contact with the metal strip 35 of the insulated disk 26 and complete the circuit before described, thus enabling the magnet 12 to apply the air-brake. In case the apparatus P should be out of order, as before mentioned, an excessive current flowing through the magnet Q when the circuit has been short-circuited will cause its armature 56 to be attracted, thus overcoming the resistance of the spring 54' and bring the contact-piece 30 out of contact with the escapement-wheel 31, permitting the clock mechanism 9 to operate. The depression of the contact-piece 30 by the sole operation of the magnet Q will enable the rod 29 to be moved down by gravity. Of course at all times the rod 29 rests upon the contact-piece 30. By reason of the slots 28 and 8² in said rod its downward movement will not interfere with the indication of the home semaphore 5 nor the distant semaphore 7.

From the operation just described it will be understood that when the apparatus P is out of order and the circuit has been short-circuited no indication of same by the semaphore 7 will be made, but the magnet Q will operate to release the clock mechanism, so that the air-brakes may be applied. The distance of the circuit-conducting portion of the disk 26 from the brush 34 for same, Fig. 11, represents the time elapsing between the operation of the magnet Q (when the apparatus P is out of order and the circuit has been short-circuited) and the application of the air-brake by the magnet 12. When the mechanism P and the magnet Q are both in working order and the circuit has been short-circuited, both will of course operate to release the escapement-wheel 31. The spring 54', it will be understood, maintains the contact-piece 30 and rod 29 at normal at all times.

In order to visually indicate to the engineer when the air-brake mechanism will be applied

by the magnets, I provide mechanism similar to the following for each magnet.

I shall describe the mechanism for visually indicating the time of operation of the electromagnet 12, which operates in connection with the insulated disk 26.

64 is a gear-wheel keyed to the spindle 22 and meshing with the gear-wheel 65, secured to or forming part of the sleeve 66, which has free movement round the sleeve 20. On the end of the sleeve 66 is a hand 67. By turning the spindle 22 in the direction indicated by arrow in Fig. 8 the overseeing engineer has set the hand 67 so that the magnet 12 will apply the air-brake in eight seconds after the operation of the apparatus O, P, and Q. The brush-holder 32 at normal position (see Fig. 11) occupies the same vertical position as the minute-hand 11. As the clock mechanism operates the minute-hand 11 and brush-holder 32 are simultaneously moved round to the right, and immediately the minute-hand 11 indicates eight seconds the brush 34 is brought in contact with the metal strip 35, as before described, thus closing the circuit to the electromagnet 12. The electromagnet 13 has been set to apply the air-brake in twelve seconds, as shown by its hand 68, the distance of which from zero corresponds to the distance of the brush 69 from the contact-strip 70 of the insulated disk 71, (see Fig. 11,) and the electromagnet 14 has been set to apply the air-brake in fifteen seconds, as shown by its hand 73, the distance of which from zero corresponds to the distance of the brush 74 from the contact-strip 75 of the insulated disk 76.

As before mentioned, I provide any suitable circuit-controlling means and an annicator in the station. The inbound station-block E³ is the section of track extending west from the station to the first insulation-points A³ and E², and the outbound station-block E⁴ is the section of track extending east from the station to the first insulation-points A³ and E². Upon referring to the drawings it will be seen that the blocks E³ and E⁴ are shorter than the blocks before described. The circuit-controlling means T, situated in the station T', is wired to the sections A² by means of wires U and V and is wired to the sections E' by wires V' and V² and is wired to the second track-rail D by wire V³. The circuit-controlling means shown consists of a spindle T', to which is secured suitable insulated disks. As shown in Fig. 4, the circuit-controlling means T is at normal, and as a consequence the engineer of an inbound train must stop in the block E³. By following the circuit from the section of the third rail E through the wire V', secured thereto, it will be seen that the brush t' rests in contact with the insulated portion of the disk t, thus opening the circuit. The opening of the circuit will of course operate the signaling-magnet O in the engineer's cab, as before described. As shown in Fig. 5, the

station agent has operated the circuit-controlling apparatus T so that the engineer of an inbound train may be notified that he is to pass through the station. When the inbound train is in the block W immediately west of the block E³, the circuit will travel in the direction indicated by arrow through the wire U, connected to one of the sections A², through the brush t² in contact with the circuit-conducting portion t³ of the insulated disk t⁴, thence through the wire t⁵, through the signal-magnet t⁶, operating the distant semaphore d of same up into the position shown, (thus signaling the station agent the position of the inbound train,) from the said signal-magnet through the wire t⁷ and brush t⁸ to the circuit-conducting portion t⁹ of the insulated disk t¹⁰, thence through the wire t down to the section A² of the first track-rail A, through the wire C to the second track-rail D, and back to the locomotive without having any effect upon the apparatus therein. When the train comes into the block E³, the current flows through the wire V' in the direction indicated by dotted arrows, following the course shown through the apparatus T to the home signal-magnet t¹², operating the home semaphore t¹³ of same into the position shown in Fig. 3, thus signaling the station agent the position of the train, the circuit being completed, as shown by dotted arrows, back to train, the current having no effect on the apparatus in the cab. As shown in Fig. 6, the station agent has operated the circuit-controlling mechanism T so as to signal the engineer of an inbound train in the block W to stop in said block. By following the circuit from the train through the track to the wire U, as shown by arrows, through the apparatus T it will be seen that the current passes from the wire U to the wire u⁶, through the brush u in contact with the circuit-conducting portion u⁷ of the insulated disk t¹⁴, through the wire t⁸ to the signal-magnet t⁹, operating the distant semaphore d of same up into the position shown, thence by the wire t¹⁰ through the brush t¹¹ in contact with the circuit-conducting portion u¹² of the insulated disk t¹³, through the wire t¹⁴ to the wire V', thence to the track-rail D, thus short-circuiting the circuit and causing either the apparatus P or Q in the cab, or both of them, to operate as before described. In case the station agent wishes to stop an outbound train still in circuit with the section V⁴ (see Fig. 7) of the third rail E he operates the circuit-controlling means T, so that the current will flow back from said section V⁴, through the wire V², to the signal-magnet t¹², operating the home semaphore t¹³ into the position shown, thence by the wire t¹⁵ to the brush u¹⁶ in contact with the circuit-conducting portion u¹⁷ of the insulated disk t¹⁸, thence by the wire t¹⁹ to the circuit-conducting portion u¹⁴ of the insulated disk t¹⁹, through the brush u¹⁵ and wire t²⁰,

down to the wire V^3 , thence through the second track-rail D, thus short-circuiting the circuit and causing the apparatus P or Q, or both, to operate as before described. In Fig. 5 7, although the distant semaphore 7 in the engineer's cab will be operated by reason of the short-circuiting of the circuit, the home semaphore t^3 will be operated in the station.

In order to prevent the operation of the 10 home semaphore t^3 and the distant semaphore 7 when the train is in the position described in Fig. 7, I have provided an alternative construction of the circuit-conducting means T, (shown in Fig. 12,) so that only the home 15 semaphore 5 in the engineer's cab will be operated. The train being in the block E⁴, Fig. 12, the current flows back through the wire e, as shown by arrows in full, to the wire t^2 , to the brush u⁵ in contact with the insulated 20 portion of the disk t^w , thus opening the circuit and causing the signal-magnet O to operate.

The end of the shaft T² has any suitable 25 pointer T⁴, which operates to the right, as shown by arrows, bearing on its face the words "Home," "Distant," "Through," and "Emergency." When the station agent wishes to 30 signal the engineer as before described, he operates the indicator T⁴ to any of the above words.

Upon referring to Fig. 3 it will be seen that I have provided any suitable wiring for overcoming the switch-centers Y. These switch-centers of course cause a break in the track-circuit, and I must provide suitable wiring to overcome same. The shoes L and M will 35 of course be wide enough apart in actual practice so as to bridge these dead-centers Y. It will of course be understood that if there 40 were no switches or tracks crossing the track described it would not be necessary for me to use two shoes. A suitable switch mechanism i is shown, which in case the train were to be switched off onto the crossover j operates so 45 as to throw the portion of the track the train is on in circuit with the said crossover, as will be clearly understood. By means of the wire l the current passes through the switch i, through the wire l', joining the third-rail section E' at l', thence by means of the wire V' 50 to and through the station T', as shown by dotted arrows, Fig. 5, and back by the wire V², following out the further circuit through the track and wiring, as shown by arrows, to the point l³, then by the wire l' back through the switch i to the wire l⁵, thence to the second track-rail D back, as shown by arrows, to the cab, the circuit being completed, as 55 shown by arrows, through the section E'. The station agent has in Fig. 3 operated his mechanism T so that the engineer will pass 60 through the station. The station agent has also operated his mechanism T in Fig. 2 so that the train will pass through, the circuit having been described in Fig. 5.

I of course do not confine myself to using the electromagnet Q, but preferably use same, so as to insure the operation of the magnets 12, 13, and 14 should the apparatus P be out of order. Neither do I confine myself to any 70 particular means for completing the circuit to the electromagnets 12, 13, and 14 after the operation of the signaling apparatus O and P and the magnet Q.

It will be understood that I may dispense 75 with the means shown and described whereby the engineer times the application of the electromagnet and the mechanism by which he visually indicates to the engineer when said magnet will apply the air-brakes. Neither do 80 I confine myself to any particular circuit-controlling means and annunciator for use in the station.

If desired, I may only use one source of 85 electrical energy for the apparatus O, P, and Q and the magnets used for applying the air-brakes.

I have described the circuits through the station and blocks merely for explanatory purposes and of course do not confine myself to 90 the wiring shown.

I do not confine myself to using the third rail divided into insulated sections in connection with the tracks A and D, as I will use an overhead-trolley wire insulated into sections in connection with electric railroads. 95

Upon referring to Fig. 14 it will be seen that e represents an electric car which is provided with the source of electrical energy O', apparatus P and O, and wiring R and R'. c' 100 is any suitable contact-arm or trolley-wheel which is held in contact with the trolley-wire c², which is divided into the sections c³. To convey the current for operating the electric car, of course any suitable conductor may be 105 used, such as a trolley-wire c⁵. c⁶ represents the usual supports for the wires c² and c⁵. The insulated sections c³ of the trolley-wire c² are preferably of the same length as the insulated sections A². The sections c³ will be wired to 110 the sections A³ by the wiring B, and the sections A² will be wired to the second track-rail D by the wiring C. The sections c³ of the trolley-wire c² are insulated from each other, as shown at c⁴. From this description it will 115 be understood that the insulated sections c³ of the trolley-wire c² correspond to the insulated sections E' of the third rail E. Of course any suitable circuit-controlling means and annunciator will be used in connection with the block 120 as constructed for electric roads. 125

I further claim the combination with my block of any electrically-operated means or air-brake-applying apparatus for the purpose set forth.

The electrical apparatus P may be an electromagnet or an ampere-coil or any electrical apparatus that will operate when more than the usual current is passing through the circuit. 130

What I claim as my invention is—

1. In a system of the class described, a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the immediately preceding insulated section of said first track-rail, and suitable wiring for connecting the said immediately preceding section of said first track-rail to the said second track-rail.
2. In a system of the class described, a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the immediately preceding insulated section of said first track-rail; suitable wiring for connecting the said immediately preceding section of said first track-rail to the said second track-rail, and a resistance-coil in the wiring for said block.
3. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail, and suitable wiring for connecting the said insulated section of said first track-rail to the said second track-rail, of a source of electrical energy placed in the cab; electrically-operated signaling means in said cab in circuit therewith and with said block for the purpose of indicating to the engineer when the circuit is open, and means for completing the circuit between said block and said source of electrical energy.
4. In a system of the class described the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated signaling means in said cab in circuit therewith and with said block for the purpose of indicating to the engineer when the circuit is open, and means for completing the circuit between said block and said source of electrical energy.

the purpose of indicating to the engineer when the circuit is open, and means for completing the circuit between said block and said source of electrical energy.

5. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail, and suitable wiring for connecting the said insulated section of said first track-rail to the said second track-rail, of a source of electrical energy placed in the cab; electrically-operated means in said cab in circuit therewith and with said block operated when the circuit is open; means for completing the circuit between said block and said source of electrical energy; electropneumatic means connected with the train-pipe for applying the air-brake; a source of electrical energy for same separate from block-circuit, and means intermediate said electrically-operated means and said electropneumatic means whereby when said electrically-operated means is operated by an open circuit, said electropneumatic means will be operated to apply the air-brake.
6. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block operated when the circuit is open; means for completing the circuit between said block and said source of electrical energy; electropneumatic means connected with the train-pipe for applying the air-brake; a source of electrical energy for same separate from block-circuit, and means intermediate said electrically-operated means and said electropneumatic means whereby when said electrically-operated means is operated by an open circuit said electropneumatic means will be operated to apply the air-brake.
7. In a system of the class described the combination with a block comprising one insulated section of a conductor which is divided into a series of insulated sections; an insulated

- section, of the first track-rail which is divided into a series of insulated sections; the second track-rail used as a common conductor for all the blocks; suitable wiring for connecting the 5 said insulated section of the said conductor to the said insulated section of the said first track-rail; suitable wiring for connecting the said insulated section of said first track-rail to the said second track-rail, and a resistance-coil in 10 the wiring for said block, of a source of electrical energy placed in the cab, electrically-operated means in said cab in circuit therewith and with said block, operated when the circuit is open; means for completing the 15 circuit between said block and said source of electrical energy; electropneumatic means connected with the train-pipe for the purpose of applying the air-brake; a source of electrical energy for same separate from block-circuit; 20 means whereby the circuit is closed for said electropneumatic means after the operation of said electrically-operated means operated when the circuit is open, and means intermediate said electrically-operated means operated 25 when the circuit is open, and said circuit-controlling means for said electropneumatic means, whereby same is set in operation to complete the circuit for said electropneumatic means.
- 30 8. In a system of the class described, the combination with a block comprising one insulated section of a conductor which is divided into a series of insulated sections; an insulated section, of the first track-rail which is divided 35 into a series of insulated sections; the second track-rail used as a common conductor for all the blocks; suitable wiring for connecting the said insulated section of the said conductor to the said insulated section of the said first track- 40 rail; suitable wiring for connecting the said insulated section of said first track-rail to the said second track-rail, and a resistance-coil in the wiring for said block, of a source of electrical energy placed in the cab, electrically-operated means in said cab in circuit therewith and with said block, operated when the 45 circuit is open; means for completing the circuit between said block and said source of electrical energy; electropneumatic means connected with the train-pipe for the purpose of applying the air-brake; a source of electrical energy for same separate from block-circuit; means whereby the circuit is closed 50 for said electropneumatic means after the operation of said electrically-operated means operated when the circuit is open; means intermediate said electrically-operated means operated when the circuit is open, and said circuit-controlling means for said electropneumatic means, whereby same is set in operation to complete the circuit for said electropneumatic means, and means for timing when said 55 circuit-controlling means for said electropneumatic means will close the circuit.
- 60 9. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block, operated when the circuit is open; means for completing the circuit between said block and said source of electrical energy; electropneumatic means connected with the train-pipe for the purpose of applying the air-brake; a source of electrical energy for same separate from block-circuit; means whereby the circuit is closed for said 65 electropneumatic means after the operation of said electrically-operated means, operated when the circuit is open; means intermediate

means for said electropneumatic means back to normal so as to open the circuit for same. 9. In a system of the class described the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block, operated when the circuit is open; means for completing the circuit between said block and said source of electrical energy; electropneumatic means connected with the train-pipe for the purpose of applying the air-brake; a source of electrical energy for same separate from block-circuit; means whereby the circuit is closed for said electropneumatic means after the operation of said electrically-operated means, operated when the circuit is open; means intermediate said electrically-operated means operated when the circuit is open, and said circuit-controlling means for said electropneumatic means, whereby same is set in operation to complete the circuit for said electropneumatic means, and means for timing when said circuit-controlling means for said electropneumatic means will close the circuit. 10. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block, operated when the circuit is open; means for completing the circuit between said block and said source of electrical energy; electropneumatic means connected with the train-pipe for the purpose of applying the air-brake; a source of electrical energy for same separate from block-circuit; means whereby the circuit is closed for said electropneumatic means after the operation of said electrically-operated means, operated when the circuit is open; means intermediate

said electrically - operated means operated when the circuit is open, and said circuit-controlling means for said electropneumatic means, whereby same is set in operation to 5 complete the circuit for said electropneumatic means; means for timing when said circuit-controlling means for said electropneumatic means will close the circuit, and means for cutting off the supply of air to said electropneumatic means, and returning said circuit-controlling means for said electropneumatic means back to normal so as to open circuit for 10 same.

11. In a system of the class described, the 15 combination with a block comprising one insulated section of a conductor which is divided into a series of insulated sections; an insulated section, of the first track-rail which is divided into a series of insulated sections; the second 20 track-rail used as a common conductor for all the blocks; suitable wiring for connecting the said insulated section of the said conductor to the said insulated section of the said first track-rail; suitable wiring for connecting the said 25 insulated section of said first track-rail to the said second track-rail, and a resistance-coil in the wiring for said block, of a source of electrical energy placed in the cab; electrically-operated means in said cab in circuit therewith and with said block, operated when the 30 circuit is open; means for completing the circuit between said block and said source of electrical energy; electropneumatic means connected with the train-pipe for the purpose of 35 applying the air-brake; a source of electrical energy for same separate from block-circuit; means whereby the circuit is closed for said electropneumatic means after the operation of said electrically-operated means, operated 40 when the circuit is open; means intermediate said electrically - operated means operated when the circuit is open, and said circuit-controlling means for said electropneumatic means, whereby same is set in operation to 45 complete the circuit for said electropneumatic means; means for timing when said circuit-controlling means for said electropneumatic means will close the circuit; means for cutting off the supply of air to said electropneumatic 50 means, and returning said circuit-controlling means for said electropneumatic means back to normal so as to open circuit for same, and means connected with said timing means for said circuit-controlling means for said electropneumatic means whereby the time of operation of said circuit-controlling means for 55 said electropneumatic means will be visually indicated.

12. In a system of the class described, the 60 combination with a block comprising one insulated section of a conductor which is divided into a series of insulated sections; an insulated section, of the first track-rail which is divided into a series of insulated sections; the second

track-rail used as a common conductor for all 65 the blocks; suitable wiring for connecting said insulated section of the said conductor to the said insulated section of the said first track-rail; suitable wiring for connecting the said insulated section of said first track-rail to the 70 said second track - rail; circuit - controlling means placed in the station and wired to said block; an annunciator in the station in circuit with said circuit-controlling means, and a resistance-coil in the wiring for said block, of a 75 source of electrical energy placed in the cab; electrically-operated signaling means in said cab in circuit therewith and with said block for the purpose of indicating to the engineer 80 when the circuit is open, and means for completing the circuit between said block and said source of electrical energy.

13. In a system of the class described, the combination with a block comprising one insulated section of a conductor which is divided 85 into a series of insulated sections; an insulated section, of the first track-rail which is divided into a series of insulated sections; the second track-rail used as a common conductor for all the blocks; suitable wiring for connecting said 90 insulated section of the said conductor to the said insulated section of the said first track-rail; suitable wiring for connecting the said insulated section of said first track-rail to the said second track - rail; circuit - controlling 95 means placed in the station and wired to said block; an annunciator in the station in circuit with said circuit-controlling means, and a resistance-coil in the wiring for said block, of a 100 source of electrical energy placed in the cab; electrically-operated means in said cab in circuit therewith and with said block operated when the circuit is open; means for completing the circuit between said block and said 105 source of electrical energy; electropneumatic means connected with the train-pipe for applying the air-brake; a source of electrical energy for same separate from block-circuit, and means intermediate said electrically-operated means and said electropneumatic means 110 whereby when said electrically - operated means is operated by an open circuit, said electropneumatic means will be operated to apply the air-brake.

14. In a system of the class described, the 115 combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said 120 insulated section of the said conductor to the said insulated section of the said first track-rail; suitable wiring for connecting the said 125 insulated section of said first track-rail to the said second track - rail; circuit - controlling means placed in the station and wired to said

block; an annunciator in the station in circuit with said circuit-controlling means, and a resistance-coil in the wiring for said block, of a source of electrical energy placed in the cab, 5 electrically-operated means in said cab in circuit therewith and with said block, operated when the circuit is open; means for completing the circuit between said block and said source of electrical energy; electropneumatic means 10 connected with the train-pipe for the purpose of applying the air-brake; a source of electrical energy for same separate from block-circuit; means whereby the circuit is closed for said electropneumatic means after the operation 15 of said electrically-operated means operated when the circuit is open, and means intermediate said electrically-operated means operated when the circuit is open, and said circuit-controlling means for said electropneumatic 20 means, whereby same is set in operation to complete the circuit for said electropneumatic means.

15. In a system of the class described, the combination with a block comprising one insulated section of a conductor which is divided 25 into a series of insulated sections; an insulated section, of the first track-rail which is divided into a series of insulated sections; the second track-rail used as a common conductor for all 30 the blocks; suitable wiring for connecting said insulated section of the said conductor to the said insulated section of the said first track-rail; suitable wiring for connecting the said insulated section of said first track-rail to the 35 said second track-rail; circuit-controlling means placed in the station and wired to said block; an annunciator in the station in circuit with said circuit-controlling means, and a resistance-coil in the wiring for said block, of a 40 source of electrical energy placed in the cab, electrically-operated means in said cab in circuit therewith and with said block, operated when the circuit is open; means for completing the circuit between said block and said source 45 of electrical energy; electropneumatic means connected with the train-pipe for the purpose of applying the air-brake; a source of electrical energy for same separate from block-circuit; means whereby the circuit is closed 50 for said electropneumatic means after the operation of said electrically-operated means operated when the circuit is open; means intermediate said electrically-operated means operated when the circuit is open, and said circuit-controlling means for said electropneumatic 55 means, whereby same is set in operation to complete the circuit for said electropneumatic means; and means for cutting off the supply of air to said electropneumatic 60 means, and returning said circuit-controlling means for said electropneumatic means back to normal so as to open the circuit for same.

16. In a system of the class described, the combination with a block comprising one insulated section of a conductor which is divided

into a series of insulated sections; an insulated section, of the first track-rail which is divided into a series of insulated sections; the second track-rail used as a common conductor for all the blocks; suitable wiring for connecting 70 said insulated section of the said conductor to the said insulated section of the said first track-rail, and suitable wiring for connecting the said insulated section of said first track-rail to the said second track-rail, of a source 75 of electrical energy placed in the cab; electrically-operated signaling means in said cab in circuit therewith and with said block for the purpose of indicating to the engineer when the circuit has been short-circuited, and means 80 for completing the circuit between said block and said source of electrical energy.

17. In a system of the class described, the combination with a block comprising one insulated section of a conductor which is divided 85 into a series of insulated sections; an insulated section, of the first track-rail which is divided into a series of insulated sections; the second track-rail used as a common conductor for all 90 the blocks; suitable wiring for connecting the said insulated section of the said conductor to the said insulated section of the said first track-rail; suitable wiring for connecting the said insulated section of said first track-rail to the said second track-rail, and a resistance- 95 coil in the wiring for said block, of a source of electrical energy placed in the cab; electrically-operated signaling means in said cab in circuit therewith and with said block for the purpose of indicating to the engineer when 100 the circuit has been short-circuited, and means for completing the circuit between said block and said source of electrical energy.

18. In a system of the class described, the combination with a block comprising one insulated section of a conductor which is divided 105 into a series of insulated sections; an insulated section, of the first track-rail which is divided into a series of insulated sections; the second track-rail used as a common conductor for all 110 the blocks; suitable wiring for connecting the said insulated section of the said conductor to the said insulated section of the said first track-rail, and suitable wiring for connecting the said insulated section of said first track-rail to the said second track-rail, of a source 115 of electrical energy placed in the cab; electrically-operated means in said cab in circuit therewith and with said block operated when the circuit has been short-circuited; means 120 for completing the circuit between said block and said source of electrical energy; electropneumatic means connected with the train-pipe for applying the air-brake; a source of electrical energy for same separate from 125 block-circuit, and means intermediate said electrically-operated means and said electropneumatic means whereby when said electrically-operated means is operated when the circuit has been short-circuited, said electro- 130

pneumatic means will be operated to apply the air-brake.

19. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block operated when the circuit has been short-circuited; means for completing the circuit between said block and said source of electrical energy; electropneumatic means connected with the train-pipe for applying the air-brake; a source of electrical energy for same separate from block-circuit, and means intermediate said electrically-operated means and said electropneumatic means whereby when said electrically-operated means is operated when the circuit has been short-circuited said electropneumatic means will be operated to apply the air-brake.

20. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab, electrically-operated means in said cab in circuit therewith and with said block, operated when the circuit has been short-circuited; means for completing the circuit between said block and said source of electrical energy; electropneumatic means connected with the train-pipe for the purpose of applying the air-brake; a source of electrical energy for same separate from block-circuit; means whereby the circuit is closed for said electropneumatic means after the operation of said electrically-operated means operated when the circuit has been short-circuited, and means intermediate said electrically-operated means operated when the circuit has been short-circuited, whereby same is set in operation to complete the circuit for said electropneumatic means.

21. In a system of the class described, the combination with a block comprising one in-

sulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab, electrically-operated means in said cab in circuit therewith and with said block, operated when the circuit has been short-circuited; means for completing the circuit between said block and said source of electrical energy; electropneumatic means connected with the train-pipe for the purpose of applying the air-brake; a source of electrical energy for same separate from block-circuit; means whereby the circuit is closed for said electropneumatic means after the operation of said electrically-operated means operated when the circuit has been short-circuited; means intermediate said electrically-operated means operated when the circuit has been short-circuited, and said circuit-controlling means for said electropneumatic means, whereby same is set in operation to complete the circuit for said electropneumatic means; and means for cutting off the supply of air to said electropneumatic means, and returning said circuit-controlling means for said electropneumatic means back to normal so as to open the circuit for same.

22. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block, operated when the circuit has been short-circuited; means for completing the circuit between said block and said source of electrical energy; electropneumatic means connected with the train-pipe for the purpose of applying the air-brake; a source of electrical energy for same separate from block-circuit; means whereby the circuit is closed for said electropneumatic means after the operation of said electrically-operated means operated when the circuit has been short-circuited; means intermediate said electrically-operated means operated when the circuit has been short-circuited, whereby same is set in operation to complete the circuit for said electropneumatic means.

cuit has been short-circuited, and said circuit-controlling means for said electropneumatic means, whereby same is set in operation to complete the circuit for said electropneumatic means, and means for timing when said circuit-controlling means for said electropneumatic means will close the circuit.

23. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block, operated when the circuit has been short-circuited; means for completing the circuit between said block and said source of electrical energy; electropneumatic means connected with the train-pipe for the purpose of applying the air-brake; a source of electrical energy for same separate from block-circuit; means whereby the circuit is closed for said electropneumatic means after the operation of said electrically-operated means, operated when the circuit has been short-circuited; means intermediate said electrically-operated means operated when the circuit has been short-circuited and said circuit-controlling means for said electropneumatic means, whereby same is set in operation to complete the circuit for said electropneumatic means; means for timing when said circuit-controlling means for said electropneumatic means will close the circuit, and means for cutting off the supply of air to said electropneumatic means, and returning said circuit-controlling means for said electropneumatic means back to normal so as to open circuit for same, and means connected with said timing means for said circuit-controlling means for said electropneumatic means whereby the time of operation of said circuit-controlling means for said electropneumatic means will be visually indicated.

35 the circuit has been short-circuited; means intermediate said electrically-operated means operated when the circuit has been short-circuited and said circuit-controlling means for said electropneumatic means, whereby same is set in operation to complete the circuit for said electropneumatic means; means for timing when said circuit-controlling means for said electropneumatic means will close the circuit, and means for cutting off the supply of air to said electropneumatic means, and returning said circuit-controlling means for said electropneumatic means back to normal so as to open circuit for same.

24. In a system of the class described, the combination with a block comprising one insulated section, of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block,

operated when the circuit has been short-circuited; means for completing the circuit between said block and said source of electrical energy; electropneumatic means connected with the train-pipe for the purpose of applying the air-brake; a source of electrical energy for same separate from block-circuit; means whereby the circuit is closed for said electropneumatic means after the operation of said electrically-operated means, operated when the circuit has been short-circuited; means intermediate said electrically-operated means operated when the circuit has been short-circuited, and said circuit-controlling means for said electropneumatic means, whereby same is set in operation to complete the circuit for said electropneumatic means; means for timing when said circuit-controlling means for said electropneumatic means will close the circuit; means for cutting off the supply of air to said electropneumatic means, and returning said circuit-controlling means for said electropneumatic means back to normal so as to open circuit for same, and means connected with said timing means for said circuit-controlling means for said electropneumatic means whereby the time of operation of said circuit-controlling means for said electropneumatic means will be visually indicated.

25. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail; suitable wiring for connecting the said insulated section of said first track-rail to the said second track-rail; circuit-controlling means placed in the station and wired to said block; an annunciator in the station in circuit with said circuit-controlling means, and a resistance-coil in the wiring for said block, of a source of electrical energy placed in the cab; electrically-operated signaling means in said cab in circuit therewith and with said block for the purpose of indicating to the engineer when the circuit has been short-circuited, and means for completing the circuit between said block and said source of electrical energy.

26. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated means in said cab in circuit therewith and with said block,

insulated section of said first track-rail to the said second track - rail; circuit - controlling means placed in the station and wired to said block; an annunciator in the station in circuit 5 with said circuit-controlling means, and a resistance-coil in the wiring for said block, of a source of electrical energy placed in the cab; electrically-operated means in said cab in circuit therewith and with said block operated when the circuit has been short-circuited; means for completing the circuit between said block and said source of electrical energy; electropneumatic means connected with the train-pipe for applying the air-brake; 10 a source of electrical energy for same separate from block-circuit, and means intermediate said electrically-operated means and said electropneumatic means whereby when said electrically-operated means is operated when the 15 circuit has been short-circuited, said electropneumatic means will be operated to apply the air-brake.

27. In a system of the class described, the combination with a block comprising one insulated section of a conductor which is divided into a series of insulated sections; an insulated section, of the first track-rail which is divided into a series of insulated sections; the second track-rail used as a common conductor 25 for all the blocks; suitable wiring for connecting said insulated section of the said conductor to the said insulated section of the said first track-rail; suitable wiring for connecting the said insulated section of said first track- 30 rail to the said second track-rail; circuit-controlling means placed in the station and wired to said block; an annunciator in the station in circuit with said circuit-controlling means, and a resistance-coil in the wiring for said block, of a source of electrical energy placed 35 in the cab, electrically-operated means in said cab in circuit therewith and with said block, operated when the circuit has been short-circuited; means for completing the circuit between said block and said source of electrical energy; electropneumatic means connected 40 with the train-pipe for the purpose of applying the air-brake; a source of electrical energy for same separate from block-circuit; means whereby the current is closed for said electropneumatic means after the operation of said electrically-operated means operated when the circuit has been short-circuited, and means intermediate said electrically-operated means 45 operated when the circuit has been short-circuited, whereby same is set in operation to complete the circuit for said electropneumatic means.

28. In a system of the class described, the combination with a block comprising one insulated section of a conductor which is divided into a series of insulated sections; an insulated section, of the first track-rail which is divided into a series of insulated sections; the second 55 track-rail used as a common conductor for all

the blocks; suitable wiring for connecting said insulated section of the said conductor to the said insulated section of the said first track-rail; suitable wiring for connecting the said insulated section of said first track-rail to the 70 said second track - rail; circuit - controlling means placed in the station and wired to said block; an annunciator in the station in circuit with said circuit-controlling means, and a resistance-coil in the wiring for said block, of a 75 source of electrical energy placed in the cab; electrically-operated means in said cab in circuit therewith and with said block, operated when the circuit has been short-circuited; means for completing the circuit between said 80 block and said source of electrical energy; electropneumatic means connected with the train-pipe for the purpose of applying the air-brake; a source of electrical energy for same 85 separate from block-circuit; means whereby the current is closed for said electropneumatic means after the operation of said electrically-operated means operated when the circuit has been short-circuited; means intermediate said electrically-operated means operated when the circuit has been short-circuited, and said circuit-controlling means for said electropneumatic means, whereby same is set 90 in operation to complete the circuit for said electropneumatic means, and means for cutting off the supply of air to said electropneumatic means, and returning said circuit-controlling means for said electropneumatic means back to normal so as to open the circuit for same. 95

29. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the 105 cab; electrically-operated signalling means operated when the circuit is open, and electrically-operated signalling means operated when the circuit has been short-circuited, both placed in the cab and on same circuit with said source of electrical energy and with said block, and means for completing the circuit between said block and said source of electrical energy. 110

30. In a system of the class described, the combination with a block comprising one insulated section of a conductor which is divided into a series of insulated sections; an insulated section, of the first track-rail which is divided into a series of insulated sections; 115

- the second track-rail used as a common conductor for all the blocks; suitable wiring for connecting the said insulated section of the said conductor to the said insulated section of the said first track-rail; suitable wiring for connecting the said insulated section of said first track-rail to the said second track-rail and a resistance-coil in the wiring for said block, of a source of electrical energy placed in the cab; electrically-operated signaling means operated when the circuit is open, and electrically-operated signaling means operated when the circuit has been short-circuited, both placed in the cab and on same circuit with said source of electrical energy and with said block; means for completing the circuit between said block and said source of electrical energy; electropneumatic means connected with the train-pipe for applying the air-brake; a source of electrical energy for same separate from block-circuit, and means intermediate said electrically-operated means operated when the circuit is open or when the circuit has been short-circuited, and said electropneumatic means, whereby when said electrically-operated means operated when the circuit is open or has been short-circuited, operates, said electropneumatic means will be operated to apply the air-brake.
31. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated signaling means operated when the circuit is open, and electrically-operated signaling means operated when the circuit has been short-circuited, both placed in the cab and on same circuit with said source of electrical energy and with said block; means for completing the circuit between said block and said source of electrical energy; electropneumatic means connected with the train-pipe for applying the air-brake; a source of electrical energy for same separate from block-circuit; circuit-controlling means for said electropneumatic means, means intermediate said electrically-operated means operated when the circuit is open or when the circuit has been short-circuited, and said circuit-controlling means for said electropneumatic means whereby when the said electrically-operated means operated when the circuit is open or has been short-circuited, operates said circuit-controlling means for said electropneumatic means will complete the circuit so that said electropneumatic means will be operated to apply the air-brake, and means for cutting off the supply of air to said electropneumatic means, and returning said circuit-controlling means for said electropneumatic means back to normal so as to open the circuit for same.
32. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail; suitable wiring for connecting the said insulated section of said first track-rail to the said second track-rail; circuit-controlling means placed in the station and wired to said block; an annunciator in the station in circuit with said circuit-controlling means, and a resistance-coil in the wiring for said block, of a source of electrical energy placed in the cab; electrically-operated signaling means operated when the circuit is open, and electrically-operated signaling means operated when the circuit has been short-circuited,

combination with a block comprising one insulated section of a conductor which is divided into a series of insulated sections; an insulated section, of the first track-rail which is divided into a series of insulated sections; the second track-rail used as a common conductor for all the blocks; suitable wiring for connecting the said insulated section of the said conductor to the said insulated section of the said first track-rail; suitable wiring for connecting the said insulated section of said first track-rail to the said second track-rail, and a resistance-coil in the wiring for said block, of a source of electrical energy placed in the cab; electrically-operated signaling means operated when the circuit is open, and electrically-operated signaling means operated when the circuit has been short-circuited, both placed in the cab and on same circuit with said source of electrical energy and with said block; means for completing the circuit between said block and said source of electrical energy; electropneumatic means connected with the train-pipe for applying the air-brake; a source of electrical energy for same separate from block-circuit; circuit-controlling means for said electropneumatic means, means intermediate said electrically-operated means operated when the circuit is open or when the circuit has been short-circuited, and said circuit-controlling means for said electropneumatic means whereby when the said electrically-operated means operated when the circuit is open or has been short-circuited, operates said circuit-controlling means for said electropneumatic means will complete the circuit so that said electropneumatic means will be operated to apply the air-brake, and means for cutting off the supply of air to said electropneumatic means, and returning said circuit-controlling means for said electropneumatic means back to normal so as to open the circuit for same.

33. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail; suitable wiring for connecting the said insulated section of said first track-rail to the said second track-rail; circuit-controlling means placed in the station and wired to said block; an annunciator in the station in circuit with said circuit-controlling means, and a resistance-coil in the wiring for said block, of a source of electrical energy placed in the cab; electrically-operated signaling means operated when the circuit is open, and electrically-operated signaling means operated when the circuit has been short-circuited,

both placed in the cab and on same circuit with said source of electrical energy and with said block, and means for completing the circuit between said block and said source of electrical energy.

34. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail; suitable wiring for connecting the said insulated section of said first track-rail to the said second track-rail; circuit-controlling means placed in the station and wired to said block; an annuiciator in the station in circuit with said circuit-controlling means, and a resistance-coil in the wiring for said block, of a source of electrical energy placed in the cab; electrically-operated signaling means operated when the circuit is open, and electrically-operated signaling means operated when the circuit has been short-circuited, both placed in the cab and on same circuit with said source of electrical energy and with said block; means for completing the circuit between said block and said source of electrical energy; electropneumatic means connected with the train-pipe for applying the air-brake; a source of electrical energy for same separate from block-circuit, and means intermediate said electrically-operated means operated when the circuit is open or when the circuit has been short-circuited, and said electropneumatic means whereby when said electrically-operated means operated when the circuit is open or has been short-circuited, operates, said electropneumatic means will be operated to apply the air-brake.

35. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail; suitable wiring for connecting the said insulated section of said first track-rail to the said second track-rail; circuit-controlling means placed in the station and wired to said block; an annuiciator in the station in circuit with said circuit-controlling means, and a resistance-coil in the wiring for said block, of a source of electrical energy placed in the cab; electrically-operated signaling means operated when the circuit is open, and electrically-operated signaling means operated when the circuit has been short-circuited, both placed in the cab and on same circuit with said source of electrical energy and with said block; means for completing the circuit between said block and said source of electrical energy; electropneumatic means connected with the train-pipe for applying the air-brake; a source of electrical energy for same separate from block-circuit; circuit-controlling means for said electropneumatic means; means intermediate said electrically-operated means operated when the circuit is open or when the circuit has been short-circuited, and said circuit-controlling means for said electropneumatic means whereby when the said electrically-operated means operated when the circuit is open or has been short-circuited, operates, said circuit-controlling means for said electropneumatic means will complete the circuit so that said electropneumatic means will be operated to apply the air-brake, and means for cutting off the supply of air to said electropneumatic means, and returning said circuit-controlling means for said electropneumatic means back to normal so as to open the circuit for same.

36. In a system of the class described, the combination with a block comprising one in-

both placed in the cab and on same circuit with said source of electrical energy and with said block; means for completing the circuit between said block and said source of electrical energy; electropneumatic means connected with the train-pipe for applying the air-brake; a source of electrical energy for same separate from block-circuit; means intermediate said electrically-operated means operated when the circuit is open or when the circuit has been short-circuited, and said electropneumatic means, whereby when said electrically-operated means operated when the circuit is open or has been short-circuited, operates, said electropneumatic means will be operated to apply the air-brake.

36. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail; suitable wiring for connecting the said insulated section of said first track-rail to the said second track-rail; circuit-controlling means placed in the station and wired to said block; an annuiciator in the station in circuit with said circuit-controlling means, and a resistance-coil in the wiring for said block, of a source of electrical energy placed in the cab; electrically-operated signaling means operated when the circuit is open, and electrically-operated signaling means operated when the circuit has been short-circuited, both placed in the cab and on same circuit with said source of electrical energy and with said block; means for completing the circuit between said block and said source of electrical energy; electropneumatic means connected with the train-pipe for applying the air-brake; a source of electrical energy for same separate from block-circuit; circuit-controlling means for said electropneumatic means; means intermediate said electrically-operated means operated when the circuit is open or when the circuit has been short-circuited, and said circuit-controlling means for said electropneumatic means whereby when the said electrically-operated means operated when the circuit is open or has been short-circuited, operates, said circuit-controlling means for said electropneumatic means will complete the circuit so that said electropneumatic means will be operated to apply the air-brake, and means for cutting off the supply of air to said electropneumatic means, and returning said circuit-controlling means for said electropneumatic means back to normal so as to open the circuit for same.

37. In a system of the class described, the combination with a block comprising one in-

sulated section of a conductor which is divided into a series of insulated sections; an insulated section, of the first track-rail which is divided into a series of insulated sections; the second 5 track-rail used as a common conductor for all the blocks; suitable wiring for connecting said insulated section of the said conductor to the said insulated section of the said first track-rail, and suitable wiring for connecting the 10 said insulated section of said first track-rail to the said second track-rail, of circuit-controlling means placed in the station and wired to said block.

38. In a system of the class described, the 15 combination with a block comprising one insulated section of a conductor which is divided into a series of insulated sections; an insulated section, of the first track-rail which is divided into a series of insulated sections; the second 20 track-rail used as a common conductor for all the blocks; suitable wiring for connecting said insulated section of the said conductor to the said insulated section of the said first track-rail, and suitable wiring for connecting the 25 said insulated section of said first track-rail to the said second track-rail, of circuit-controlling means placed in the station and wired to said block, and an annunciator in the station in circuit with said circuit-controlling means.

39. In a system of the class described, the 30 combination with a block comprising one insulated section of a conductor which is divided into a series of insulated sections; an insulated section, of the first track-rail which is divided into a series of insulated sections; the second 35 track-rail used as a common conductor for all the blocks; suitable wiring for connecting the said insulated section of the said conductor to the said insulated section of the said first track-rail; suitable wiring for connecting the said 40 insulated section of said first track-rail to the said second track-rail, and a resistance-coil in the wiring for said block, of circuit-controlling means placed in the station and wired to said block, and an annunciator in the station in 45 circuit with said circuit-controlling means.

40. In a system of the class described, the 50 combination with a block, of a source of electrical energy placed in the cab, electropneumatic means in circuit therewith and connected with said train-pipe, and means in circuit with said block operated when the circuit has been opened or short-circuited for the purpose of operating said electropneumatic means so 55 as to apply the air-brake.

41. In a system of the class described, the 60 combination with the train-pipe, and a valve controlling air-pressure in same, of a normally deenergized magnet connected to said valve; means for energizing said normally deenergized magnet so that it will operate said valve to control air-pressure within said train-pipe, and means for timing the operation of said normally deenergized magnet.

65 42. In a system of the class described, the

combination with the train-pipe, and a valve controlling air-pressure in same, of a normally deenergized magnet connected to said valve; means for energizing said normally deenergized magnet so that it will operate said valve 70 to control air-pressure within said train-pipe; means for timing the operation of said normally deenergized magnet, and means for visually indicating when said normally deenergized magnet will operate. 75

43. In a system of the class described, the combination with normally energized electrically-operated means operated when the circuit for same is open, of normally deenergized electropneumatic means; a train-pipe with which 80 said normally deenergized electropneumatic means is connected; means intermediate said normally energized electrically-operated means and said normally deenergized electropneumatic means whereby when said normally energized electrically-operated means is 85 operated by an open circuit, said normally deenergized electropneumatic means will be operated to apply the air-brake, and means for timing the operation of said normally deenergized electropneumatic means. 90

44. In a system of the class described, the combination with normally energized electrically-operated means operated when the circuit for same is short-circuited, of normally deenergized electropneumatic means; a train-pipe with which said normally deenergized electropneumatic means is connected; means intermediate said normally energized electrically-operated means and said normally deenergized 95 electropneumatic means whereby when said normally energized electrically-operated means is operated when the circuit has been short-circuited, said normally deenergized electropneumatic means will be operated to 100 apply the air-brake, and means for timing the operation of said normally deenergized electropneumatic means. 105

45. In a system of the class described, the combination with normally energized electrically-operated means operated when the circuit for same is open; normally energized electrically-operated means operated when the circuit for same has been short-circuited, both of said means being on the same circuit, of normally deenergized electropneumatic means; the train-pipe with which said normally deenergized electropneumatic means is connected; means intermediate said normally energized electrically-operated means operated when the circuit is open or 110 has been short-circuited, and said normally deenergized electropneumatic means, whereby, when said normally energized electrically-operated means operated when the circuit is open or 115 has been short-circuited operates, said normally deenergized electropneumatic means will be operated to apply the air-brake, and means for timing the operation of said normally deenergized electropneumatic means. 120

125

130

46. In a system of the class described, the combination with normally energized electrically-operated means operated when the circuit for same is open; normally energized electrically-operated means operated when the circuit for same has been short-circuited, both of said means being on the same circuit, of normally deenergized electropneumatic means; the train-pipe with which said normally deenergized electropneumatic means is connected; means intermediate said normally energized electrically-operated means operated when the circuit is open or when the circuit has been short-circuited, and said normally deenergized electropneumatic means, whereby, when said normally energized electrically - operated means operated when the circuit is open or has been short-circuited operates, said normally deenergized electropneumatic means 70
10 will be operated to apply the air-brake; means for timing the operation of said normally deenergized electropneumatic means, and means for visually indicating when said normally deenergized electropneumatic means will operate.
15 25 47. In a system of the class described, the combination with normally energized electrically-operated means operated when the circuit for same is open; normally energized electrically-operated means operated when the circuit for same has been short-circuited, and a source of electrical energy for same, both of said means being on the same circuit, of normally deenergized electropneumatic means; the train-pipe with which said normally deenergized electropneumatic means is connected; a separate source of electrical energy for said normally deenergized electropneumatic means, means intermediate said normally energized electrically - operated means operated when the circuit is open or when the circuit has been short-circuited, and said normally deenergized electropneumatic means whereby, when said normally energized electrically-operated 90
30 35 40 45 50 means operated when the circuit is open or has been short-circuited operates, said normally deenergized electropneumatic means will be operated to apply the air-brake; and means for timing the operation of said normally deenergized electropneumatic means.
55 60 65 70 75 80 85 90 95 100 105 110 115 120 125 130 48. In a system of the class described, the combination with normally energized electrically-operated means operated when the circuit for same is open; normally energized electrically-operated means operated when the circuit for same has been short-circuited, and a source of electrical energy for same, both of said means being on the same circuit, of normally deenergized electropneumatic means; the train-pipe with which said normally deenergized electropneumatic is connected; a separate source of electrical energy for said normally deenergized electropneumatic means; means intermediate said normally energized electrically-operated means operated when the circuit is open or when the circuit has been short-circuited; electropneumatic means for applying the air-brake when said electrically-operated means operated when the circuit is open or has been short-circuited, operates; means for completing the circuit between said block and said source of electrical energy, and means for timing the operation of said electropneumatic means.
80 85 90 95 100 105 110 115 120 125 130 49. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail, and suitable wiring for connecting the said insulated section of said first track-rail to the said second track-rail, of a source of electrical energy placed in the cab, electrically-operated signaling means in said cab in circuit therewith and with said block for the purpose of indicating to the engineer when the circuit is open or when the circuit has been short-circuited; electropneumatic means for applying the air-brake operated when said electrically-operated means operated when the circuit is open or has been short-circuited, operates, and means for completing the circuit between said block and said source of electrical energy.
50 55 60 65 70 75 80 85 90 95 100 105 110 115 120 125 130 51. In a system of the class described, the combination with a block comprising one insulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail, and suitable wiring for connecting the said insulated section of said first track-rail to the said second track-rail, of a source of electrical energy placed in the cab; electrically-operated signaling means in said cab in circuit therewith and with said block for the purpose of indicating to the engineer when the circuit is open or when the circuit has been short-circuited; electropneumatic means for applying the air-brake when said electrically-operated means operated when the circuit is open or has been short-circuited, operates; means for completing the circuit between said block and said source of electrical energy, and means for timing the operation of said electropneumatic means.

sulated section of a conductor which is divided into a series of insulated sections; an insulated section, of the first track-rail which is divided into a series of insulated sections; the second track-rail used as a common conductor for all the blocks; suitable wiring for connecting said insulated section of the said conductor to the said insulated section of the said first track-rail, and suitable wiring for connecting the 5 said insulated section of said first track-rail to the said second track-rail, of a source of electrical energy placed in the cab, electrically-operated signaling means in said cab in circuit therewith and with said block for the purpose 10 of indicating to the engineer when the circuit is open or when the circuit has been short-circuited; electropneumatic means for apply- 15

ing the air-brake operated when said electrically-operated means operated when the circuit is open or has been short-circuited, operates; 20 means for completing the circuit between said block and said source of electrical energy; means for timing the operation of said electro-pneumatic means, and means for visually indicating when said electropneumatic means 25 will operate.

In testimony whereof I have signed my name to this specification in the presence of two subscribing witnesses.

JOHN ALEXANDER WHYTE.
